RADIO RECEIVING SYSTEM

Filed Feb. 17, 1925

UNITED STATES PATENT OFFICE

SAMUEL COHEN, OF BROOKLYN, NEW YORK, ASSIGNOR TO GENERAL INSTRUMENT CORPORATION, OF NEW YORK, N. Y., A CORPORATION OF NEW YORK

RADIO RECEIVING SYSTEM

Application filed February 17, 1925. Serial No. 9,753.

My invention relates broadly to electron tube amplification systems and more particularly to circuit arrangements for stabilizing the operation of sensitive electron tube circuits.

5 One of the objects of my invention is to provide an electron tube amplification system which may include a large number of stages of amplification for increasing feeble electrical energy to energy at large amplitude 10 without interference arising from the oscillatory currents in the several amplification circuits.

Another object of my invention is to provide an electron tube amplification system 15 wherein selected stages of amplification may be equipped with supplemental circuits operating to eliminate the effect of undesired oscillatory currents upon a desired signaling frequency during its passage through the 20 amplification system.

Still another object of my invention is to provide a supplemental circuit arranged for connection to the circuits of electron tube 25 amplification systems whereby undesired oscillatory currents may be absorbed from the system and dissipated in the form of eddy current or hysteresis losses, in such manner that the undesired oscillatory currents will 30 have no effect upon the signaling currents.

A further object of my invention is to provide an impedance circuit which may be connected with the circuits of an electron tube amplification system for regulating the input 35 impedance of the electron tube for shifting the phase relationship of the voltages across the grid and plate circuits in such manner that the oscillatory currents in the amplification system are substantially eliminated.

40 A still further object of my invention is the provision of an impedance circuit arranged to be so connected with the electrodes of electron tubes in an amplification system that the phase relationship of the voltages across the input and output circuits of each of the tubes 45 may be regulated to be slightly less than 180 degrees, whereby the amplification circuits are rendered stable and are not affected by undesired oscillatory currents.

50 My invention resides in the location of an

impedance circuit with respect to the input and output circuits of an electron tube in an amplification system which includes an inductance in the input circuit of the electron tube system or an inductance equivalent thereto, whereby regulation of the phase of the voltages existing across the input and output circuits of the tube may be secured independent of the frequency of the incoming signaling energy.

55 My invention finds particular application in radio frequency amplification circuits where it is desired to amplify signaling currents over a broad band of frequencies. Heretofore in the art it has been proposed to balance or neutralize the capacity coupling between the electrodes of the electron tubes in an amplification system and for this purpose values of inductance and capacity have been connected with the circuits of electron tubes 60 in the amplifier for balancing the effects of the intra-electrode capacities within the electron tubes. This method of balancing capacity coupling has been dependent upon the particular values of capacity coupling between the electrodes of the electron tubes and accordingly directly dependent upon the characteristics of the electron tubes in the system. Manufacturers of electron tubes 65 have departed from the established characteristics of tube construction with the result that circuits designed to eliminate capacity coupling in a multistage amplifier have failed to function. By my present invention I increase the flexibility of the amplification circuit to the extent that tubes of widely different characteristics may be employed and the impedance circuits supplementing the circuits of the electron tubes readily adjusted to shift the phase relationship of the voltages in the 70 input and output circuits of the tubes for the elimination of oscillations in the amplification system.

75 My invention will be more clearly understood from the specification hereinafter following, by reference to the accompanying drawing, wherein:

Figure 1 is a theoretical diagram illustrating the intra-electrode capacities within an electron tube; Fig. 2 is a theoretical di-

agram illustrating the connections which I provide for the impedance circuit between the input and output circuits of the electron tube amplification system; Fig. 3 illustrates an application of my invention to a radio frequency amplification system in a radio receiving apparatus; Fig. 4 illustrates the application of my invention to a multistage radio frequency amplifier in connection with a detector circuit for a radio receiving apparatus; and Fig. 5 shows an application of the impedance circuit of my invention connected with respect to a single stage of radio frequency amplification preceding a detector circuit in a radio receiving system.

By the employment of the impedance circuit arrangement illustrated in the drawing, I have successfully operated multistage radio frequency amplifiers wherein the limitation as to the number of stages which may be employed depends not upon the electrostatic coupling between the electrodes of the electron tubes in the system, but directly upon the magnetic coupling of the interstage coupling transformers. The shielding of the coupling transformers either magnetically or electrostatically eliminates this undesired coupling effect. The values of the impedance circuit which I provide as supplemental connections between the input and output circuits of the electron tubes are so proportioned with respect to the value of the inductance in the input circuit, or the equivalent of such inductance, that the phase of the voltage relation between the grid and plate circuits is shifted so that the phase relationship is slightly less than 180 degrees. In this condition the circuits become stable and oscillatory currents are eliminated. The phase relationship may be controlled for tubes of different characteristic for modifying the values of the resistance, capacity and inductance included in the impedance circuit until that point is found at which interference due to oscillatory currents is eliminated. By shifting the phase of the voltages between the input and output circuits of the tubes, the resulting voltage which normally directly excites the tube circuits into oscillation, becomes substantially nil and correspondingly the current is so infinitesimal that oscillatory currents are practically absent from the tube circuits.

Referring more particularly to the drawing, Figure 1 represents the distribution of the intra-electrode capacities within an electron tube wherein the letters G, P and F, designate the grid, plate and filament, respectively. The inherent capacity existing between the grid and plate electrodes has been designated by reference characters G_cP . The inherent capacity existing between the filament electrode and the plate has been designated by the reference characters F_cP , and likewise the inherent capacity existing

between the grid and the filament has been designated by the reference characters G_cF .

In Fig. 2 these inherent capacities have been illustrated by circuit diagram wherein an input circuit containing inductance 1 is coupled to an inductance 2 which is connected across the terminals 3 and 4 of the capacity system. The output circuit of the system includes an inductance 5 and a source of high potential energy designated at 6, the inductance 5 being coupled with the inductance system 7. An impedance circuit 8 is provided connected to a variable contact 9 along inductance 2 and to the point 10 in the capacity system. A shunt path inductance L_3 of the input inductance L_1 , indicated by reference character 2, is provided between the point 3 and point 10 in the capacity system of the impedance circuit 8. The inductance L_3 must be apportioned with such relation with regard to the impedance circuit 8, that the phase relationship of the grid and plate current is slightly less than 180 degrees. The impedance circuit may include a variable resistance and capacity. It is to be noted that the resistance in this impedance circuit is used primarily for the purpose of changing the 180 degree phase relationship, provided that the circuit which includes the impedance circuit contains the tube capacities of the corresponding inductances, that is in Figure 2, the value of inductance L_3 , the value of impedance 8 and the value of capacity G_cP .

In Fig. 3 a practical application of my invention is illustrated at a radio receiving station employing the antenna ground system 11 and 14, including the primary winding 12 in circuit therewith. Secondary inductance 15 is coupled with the primary winding 12 and is tuned by variable condenser 16 to the incoming signaling frequency. The electron tube 17 functions as a radio frequency amplifier having primary inductance 18 in the output circuit thereof. The impedance circuit is illustrated as comprising capacity 19 and resistance 20, both of which may be adjustable to enable the circuit to cooperate with electron tubes of different characteristics. The secondary inductance 15 has a portion thereof indicated at L_s and included in circuit with the adjustable impedance 8. The radio frequency amplifier has its output circuit coupled with the secondary inductance 21 which is tuned by condenser 22. This circuit connects with the detector tube 24, including grid leak and grid condenser 23. A responsive device 25 is shown connected in the output circuit of the detector tube 24. The cathodes of the several tubes are heated from battery 27 while the plate potential for the tubes is supplied from battery 26. A by-pass condenser 28 is provided in the output circuits. The value of inductance L_s , capacity 19 and resistance 20

is varied in accordance with the characteristics of the tube to regulate the input impedance for shifting the phase of the voltage relation between the input and output circuits providing a circuit where the undesired currents are dissipated.

In Fig. 4 I have shown a cascade radio frequency amplifier and detector circuit at a radio receiving circuit including two stages of radio frequency amplification. The impedance circuit 8, including capacity 19 and resistance 20, is connected in circuit with inductance L_3 from a point in the input circuit of tube 17 while an additional impedance circuit, comprising condenser 29 and resistance 30, is also connected in circuit with the inductance L_3 from a point in the input circuit of electron tube 31 forming the second stage of radio frequency amplification. The inductance L_3 in the output circuit of tube 17 in the circuit arrangement illustrated in Fig. 4 is equivalent to the inductance L_3 consisting of a portion of the secondary winding 15 in Fig. 3. The inductance L_3 in this instance constitutes the primary winding of the coupling transformer which is associated with secondary winding 33 functioning to transfer the energy to the second stage of radio frequency amplification formed by tube 31. The secondary winding 33 is tuned by variable condenser 32 and the output energy delivered through winding 34 to a detector circuit as hereinbefore described. It will be observed that the phase of the input and output currents in the electron tubes 17 and 31 is displaced by control means independent of frequency and each of the impedance circuits being adjustable permits the amplification system to function efficiently with tubes of widely different characteristics.

In Fig. 5 I have shown the impedance circuit 8 associated with a single stage of radio frequency amplification and connected between a point 35 in the input circuit of the radio frequency amplification circuit connected with tube 17 and the lower terminal of inductance L_3 in the output circuit of the radio frequency amplification system. The impedance circuit in this relationship operates, as hereinbefore described, to shift the phase relationship of the input and output voltages stabilizing the radio frequency amplifier independent of the operating frequency. It will be observed that the principle which I employ of shifting the phase relationship of the input and output currents is applicable to radio frequency amplification systems independent of tube characteristics and the operating frequency. These factors permit wide application of the invention to electron tube circuits and, accordingly, the applications of the invention described herein are to be considered in the illustrative sense rather than the limiting sense. It will also be understood that modifications of my inven-

tion may be made and that I intend no limitations upon the invention other than are imposed by the scope of the appended claims.

What I claim and desire to secure by Letters Patent of the United States is as follows:

1. An amplification system comprising in combination a plurality of electron tubes, each having grid, cathode and plate electrodes, a tuned input and an output circuit interconnecting said electrodes, means inter-linking the output circuit of one of said electron tubes with the input circuit of a succeeding electron tube, and an impedance circuit connected between points on the grid sides of said tuned input circuits of succeeding electron tubes and a point in the output circuit of each of said electron tubes for stabilizing the operation of said amplification system.

2. An amplification system comprising in combination a plurality of electron tubes, each having grid, cathode and plate electrodes, input and output circuits interconnecting said electrodes, means inter-linking the output circuit of one of said electron tubes with the grid sides of the input circuit of a succeeding electron tube, an impedance circuit arranged for connection between points in the input circuits of succeeding electron tubes and including an element in the output circuit of each of said electron tubes for stabilizing the operation of said amplification system.

3. An amplification system comprising in combination a plurality of electron tubes, each having grid, cathode and plate electrodes, input and output circuits interconnecting said electrodes, means inter-linking the output circuit of one of said electron tubes with the input circuit of a succeeding electron tube, and an impedance circuit comprising a plurality of adjustable elements connected between points on the grid sides of the input circuits of succeeding electron tubes with a connection between a midpoint in said impedance circuit with a point in the output circuit of one of said electron tubes for stabilizing the operation of said amplification system.

4. An amplification system comprising in combination a plurality of electron tubes, each having grid, cathode and plate electrodes, input and output circuits interconnecting said electrodes, means inter-linking the output circuit of one of said electron tubes with the input circuit of a succeeding electron tube, an impedance circuit including a plurality of similar elements connected in series with the extremities of the impedance circuit connected to points on the grid sides of the input circuits of succeeding electron tubes, and a connection from the midpoint between a pair of said similar elements in said impedance circuit with a point in the output circuit of one of said electron tubes for stabilizing the operation of said amplification system.

5. An amplification system comprising in combination a plurality of electron tubes, each having grid, cathode and plate electrodes, input and output circuits interconnecting said electrodes, means inter-linking the output circuit of one of said electron tubes with the input circuit of a succeeding electron tube, an impedance circuit comprising a plurality of resistance and capacity elements connected in series with the opposite terminals of said circuit connected with said capacity elements and with points in the input circuits of succeeding electron tubes, said resistance elements being mutually interconnected to each other and to the opposite terminals of said capacity elements, and a connection between said resistance elements and a point in the output circuit of one of said tubes for stabilizing the operation of said amplification system. 70
